(57) **CLAIM**

We claim the ornamental design for a feeding stand, as shown and described.

DESCRIPTION

FIG. 1 is a reduced perspective view of a feeding stand;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The portions shown in broken lines do not form part of the claimed design.
